UNITED STATES PATENT OFFICE.

ARTHUR WATKINSON, OF LONDON, ENGLAND.

WINDOW OR THE LIKE.

Application filed March 17, 1920. Serial No. 366,654.

To all whom it may concern:

Be it known that I, ARTHUR WATKINSON, a subject of the King of England, residing at Willesden, London, N. W., England, have 5 invented certain new and useful Improvements in Windows or the like, (for which on June 18, 1914, I filed in Great Britain application No. 14688/14, published July 8, 1915, and sealed Sept. 2, 1915; and on June 12, 10 1915, filed application Serial No. 479,014 in France, said French application having been granted November 9, 1915, and published February 2, 1916), of which the following is a specification.

15 The present invention relates to improvements in windows or the like, and concerns more particularly sliding windows.

In connection with railway carriages it has been proposed to use plate glass windows 20 which are not framed by a sash in the usual manner, but which slide directly in a window frame. There has been a difficulty, however, in connection with such a construction inasmuch as the glass has a tendency to rattle, 25 and various devices have been proposed to overcome this disadvantage, but these have not been entirely successful. It is an object of the present invention to provide means in which such a frameless or sashless window 30 may slide easily without rattling, which means shall be cheap and simple to manufacture and put in place.

According therefore to the present invention there is provided as a new article of 35 manufacture a metal strip of channel-section combined with a lining of felt or like material attached thereto, by having an edge between a side wall of the strip and a tongue, lip or the like which is preferably continuous, extending from the side wall and overhanging the edge of the lining and extending 40 down over and into the marginal portion of the lining.

45 A convenient construction according to the present invention will now be described with reference to the accompanying drawing which is a perspective view of a short length of the aforesaid strip.

The strip A is of brass which is of channel-shape in cross-section and the inside of the channel is lined with felt B. In the manufacture of the strip the upper margin of the channel which is an upward continuation of the channel-sides is turned inwards 50 and downwards so that the lower part of the down-turned portion will overlie the top

margin of the felt. Next, this downwardly-turned portion is pressed towards the channel side in order that it may hold the felt between it and the side-wall as at a and thus 55 attach the felt to the strip A, so that the felt will not be movable longitudinally, nor will it have its edges exposed to dirt and wet or frayed by the sliding movement of a window along the felt lined channel. The 60 thickness of the channel side-walls and their inturned portions is such that the surface of the inturned portion is below the surface of the adjacent felt so that the window in sliding up and down will slide upon the felt and 65 not upon the inturned metal.

In using such strip as a window frame in railway carriages, two long lengths of the strip are fixed to the panelling and are joined by a short strip at the top so that when 70 the window is closed three of its edges will be in contact with the felt, which will tend to hold it in place. When the window is lowered its top edge will leave the cross strip, but it will still be gripped by the felt 75 in the strips at the two sides so that it will not rattle.

The invention has been described with reference to a frameless or sashless window, but is not limited thereto as it would also 80 be useful in connection with a window having a sash. In this case, of course, the channel would have to be of wider section in order to accommodate the thicker window edge due to the sash. 85

Further a window sash itself might be formed of such strip, which would be joined together at the four corners in any convenient manner. In such a case the felt would prevent jars upon the frame from reaching 90 the glass of the window. A window sashed in this manner might be located in a window-frame formed of a strip according to the present invention.

Reference has been made to windows used 100 in railway carriages, but the invention is equally useful in connection with sliding windows of motor cars, or other vehicles or of ships or in fact any sliding window, and in particular any sliding frameless or sashless window.

What I claim as my invention and desire to secure by Letters Patent is:—

The combination of a metal strip of channel section having the adjacent sides thereof 110 extending at substantially right angles to each other to form three flat sides one of

which is adapted to directly cooperate with and bear against a flat surface on a window frame, the remaining two sides each having its free edge bent inwardly and downwardly 5 to provide a recess communicating with the channel and also to provide a shoulder presented toward the bottom of said channel, a lining of cushioning material of greater thickness than the width of said shoulders disposed in said channel with the outer portion of each edge forced into the respective 10 recess and the inner portion of said edge in abutting frictional engagement with the respective shoulder, each side wall of the lining extending to a plane inwardly of the 15 respective shoulder, said lining being readily replaceable and disengageable from said channel member, and a glass sheet directly engaged by said lining.

In testimony whereof I affix my signature.

ARTHUR WATKINSON.
